(57) **CLAIM**

The ornamental design for a camera, as shown and described.

DESCRIPTION

FIG. 1 is a top, front and side perspective view of a camera showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational view thereof from the right of FIG. 2; and,

FIG. 7 is a side elevational view thereof from the left of FIG. 2.

The parts shown in broken line are shown only to illustrate the environment of the present invention and form no part of the present invention.
